TORPEDO

Ellison S. Purington, Gloucester, Mass., assignor
to John Hays Hammond, Jr., Gloucester,
Mass.

Application April 6, 1936, Serial No. 72,915

10 Claims. (Cl. 114—21)

This invention relates to the control of self propelled moving bodies, and more particularly to a new and improved means for controlling the action of a torpedo.

5 The invention provides a control device which becomes effective when the torpedo misses its objective and operates to redirect the torpedo for producing a hit.

In one embodiment an antenna of conducting 10 material, which is insulated from the surrounding medium, is trailed behind the torpedo in a position to contact with the hull of the enemy ship should the torpedo pass in front thereof. The contact with the hull causes the insulation 15 to be disrupted thereby closing a circuit which is utilized for redirecting the torpedo toward the enemy ship.

The direction in which the torpedo must turn is determined by the direction of travel of the 20 enemy ship and means is provided for manually setting the apparatus to cause the proper direction of turn before the torpedo is fired.

The insulated antenna may be provided with a conducting covering in order to minimize the 25 resistance path through the medium in which the torpedo is traveling.

The invention also consists in certain new and original features of construction and combinations of parts hereinafter set forth and claimed.

30 Although the novel features which are believed to be characteristic of this invention will be particularly pointed out in the claims appended hereto, the invention itself, as to its objects and advantages, the mode of its operation and the 35 manner of its organization may be better understood by referring to the following description taken in connection with the accompanying drawings forming a part thereof, in which

Fig. 1 is a diagrammatic sectional view of a 40 portion of a torpedo embodying the present invention,

Fig. 2 is a longitudinal sectional view of a portion of the tail of the torpedo,

Fig. 3 is a transverse section along line 3—3 45 of Fig. 1,

Fig. 4 is a diagrammatic illustration of the course of the torpedo under the influence of the control device.

Fig. 5 is an enlarged sectional view of a modified form of the tail of the torpedo; and

Fig. 6 is an enlarged sectional view of another modified form of the tail of the torpedo.

Like reference characters denote like parts in the several figures of the drawings.

55 In the following description and in the claims

parts will be identified by specific names for convenience, but they are intended to be as generic in their application to similar parts as the art will permit.

Referring to Figs. 1 to 3, there is shown a 5 water-borne torpedo forming a carrier of explosives, having a water tight hull 10 and arranged to be propelled by a pair of propellers 11. The propellers 11 are mounted on a pair of concentric shafts, including an outer shaft 12 and an 10 inner shaft 13. The shafts 12 and 13 are directly connected to a driving means 15. A gear 17 is secured to the outer shaft 12 and operatively engages two gears 18 and 19 to cause the rotation of two shafts 20 and 21.

For varying the direction of the movement of the torpedo about a vertical axis so as to steer the torpedo in azimuth, there is provided a pair of blade rudders 25, secured to a pair of rotatable rudder posts 26 whereby the rudders 25 may be moved relative to the torpedo to control the direction of the movement thereof. The rudder posts 26 are rigidly connected by a yoke 27 which may be moved according to requirements by a connecting rod 28, having one 25 end pivotally connected to the yoke 27. The other end of the connecting rod 28 is pivotally secured to a piston rod 29 of a piston 30 which is mounted for reciprocating movement in a cylinder 31. This cylinder is the steering cylinder 30 of a standard torpedo steering mechanism and is controlled in a well known manner by the usual gyroscopic apparatus 32. The apparatus thus far described is set forth more in detail in U. S. Patent No. 1,857,150 issued May 10, 1932 to 35 John Hays Hammond, Jr. and only so much thereof is shown herein as is necessary to an understanding of the present invention.

In accordance with the present invention, the cylinder 31 is supplied with compressed air from 40 a pipe 35, which communicates with a valve 36. This valve is provided with two pistons 37 and 38 mounted on a valve stem 39, to the ends of which are secured two collars 40 and 41. Between the collar 41 and the valve 36 is a spring 45 42. The valve 39 is supplied with compressed air from any suitable source, not shown, by means of a pipe 43.

The valve 36 is connected by means of a pipe 44 to a rotary valve 45 which is rotatably 50 mounted in a valve casing 46. The rotary valve 45 is provided with a square shaped recess 34 (Fig. 3). The valve casing 46 is provided with an exhaust port 47 and is connected by means of two pipes 48 and 49 to the opposite ends of 55

a cylinder 50 which is provided with a piston 51 which is connected by a piston rod 52 and a link 53 to an arm 55. The arm 55 is pivoted at its upper end to a bracket 56 which forms part 5 of the valve casing 46. The arm 55 is provided at its lower end with a slot 57 in which slides a pin 58 secured to the connecting rod 28.

The collar 41 on the valve stem 39 is normally engaged by a trip member 60 which forms 10 the core of a solenoid 61 and is held in the position shown by means of a spring 62. The solenoid 61 is in a circuit including a battery 63 and the front contact of a relay 65. The solenoid 61 is connected by a conductor 66 to one 15 contact 67 of a distance gear mechanism 68, the other contact 69 of which is connected by a conductor 70 to the armature of the relay 65. The two contacts 67 and 69 are secured to, but insulated from, a shaft 71. This shaft passes 20 through a water tight bearing 72 and at its upper end is provided with a pointer 73 and a square head 75 which may be engaged by an adjusting tool so that the contacts 67 and 69 may be rotated to any desired position which is indicated 25 by means of the pointer 73, cooperating with a suitable scale not shown. The contact 67 is provided with a button 76 of insulating material, which engages a circular cam 77 provided with a cam projection 78. This cam is driven at a 30 very slow rate of speed from the shaft 20 by means of the reduction gearing 79.

One side of the winding of the relay 65 is grounded to the hull of the torpedo 10 at 80. The other side of the winding of this relay is 35 connected through a battery 81 to a conductor 82, which is insulated by a covering of rubber 83 or other suitable insulation. This insulated conductor passes through a pipe 84 to the exterior of the torpedo. This conductor is cov- 40 ered with insulation over its entire length so that normally it is not in contact with the medium surrounding the torpedo.

Shortly before the torpedo is fired, the distance gear 68 is set by turning the shaft 71 a 45 given amount as indicated by the pointer 73. This is done by the use of a socket wrench or adjusting tool which fits over the square head 75 of the shaft 71. This setting is made considerably less than the estimated range of the 50 enemy. The distance gear switch 67-69 is thus moved to a given position with respect to the cam 77, the angular distance between the cam projection 78 and the button 76 being proportional to the distance through which the 55 torpedo will travel before the distance gear switch is closed.

If the enemy is moving to the left as shown in Fig. 4, the rotary valve 45 is turned to the position shown in Fig. 1 by means of a suitable tool 60 inserted in the square shaped recess 34, thus operatively connecting the pipe 49 to the pipe 44 and the pipe 48 to the exhaust port 47.

When the torpedo is fired, the insulated wire 62 is unreeled from a detachable reel or other 65 suitable means not shown. As the torpedo progresses, the shaft 20 is rotated by means of the gears 17 and 18, thus causing the cam 77 to be slowly rotated by means of the reduction gearing 79. This continues until the torpedo has 70 traveled the distance set on the distance gear 68. After it has traveled this distance, the cam projection 78 will engage the button 76, thus lifting the contact 67 into engagement with the contact 69. It is thus seen that the solenoid 75 61 is in an inoperative condition until the dis-

tance gear closes the contacts 67 and 69 as just described. Hence the solenoid 61 will be maintained in an inoperative condition until the torpedo has reached the proximity of the target, thus preventing the premature operation 5 of the control mechanism due to the shock of launching, etc.

During the run, the vertical rudders 25 of the torpedo are controlled in a well known and 10 standard manner by means of the steering cylinder 31, the action of which is controlled by the gyroscope 32. The torpedo then runs under the control of the gyroscope until it reaches the enemy line.

In case the torpedo should fail to strike a 15 ship but should pass in front of it, the hull of the enemy ship will contact the insulated wire 82 and disrupt the insulation 83, thus allowing the metallic conductor 62 to come in contact 20 with the water and to complete a circuit from the battery 81 through the conductor 82, the water surrounding the torpedo, the metallic hull 10, and the relay 65 back to the battery 81. This will energize the relay 65, thus closing 25 a circuit from the battery 63 through the armature of the relay 65, conductor 70, contacts 69 and 67, conductor 66, and the solenoid 61 back to the battery 63, thereby energizing the solenoid 61 and causing the core 60 to be moved downwardly, to release the collar 41. The valve stem 39, together with the pistons 37 and 38, are then moved to the right under the action of the spring 42, to shut off the supply of compressed air to the pipe 35 and connect this pipe to the atmosphere, thereby rendering the gyroscopic control ineffective. At the same time, compressed air is supplied to the pipe 44, thence through the rotary valve 45 to the pipe 49 and to the right-hand end of the cylinder 50, to cause the piston 51 to be moved to the left and, by means 30 of the piston rod 52 and link 53, to rotate the arm 55 in a clockwise direction. This arm, by means of the pin 58, moves the connecting rod 28 to the left, thereby turning the rudders 11 to port to cause the torpedo to be steered to the left as seen in Fig. 4. The torpedo will then follow the curve 85 until it strikes the enemy vessel, as at 86 Fig. 4, or until its power 35 is expended.

If the enemy is moving to the right, the rotary valve 45 is turned through a quarter revolution 40 from the position shown in Fig. 1, thus connecting the pipe 48 to the pipe 44 and the pipe 49 to the exhaust port 47. In this instance when 45 the enemy ship contacts the tail 82, compressed air will pass from the pipe 44 to the left-hand side of the cylinder 50 which will cause the arm 55 to be rotated in a counter clockwise direction. This motion will cause the connecting rod 28 50 to be moved to the right and thereby turn the rudders to starboard to cause the torpedo to be steered to the right.

In order to minimize the resistance path 55 through the water, the insulated conductor 82 65 may be provided with a conducting covering 98 as shown in Fig. 5 which surrounds the insulation 83 and which is grounded to the hull 10. This conducting covering may be made of any 70 suitable flexible material such as a woven metallic covering which however is made of very fine wire so as to be easily broken on contact with the hull of the enemy ship. In this way the conducting path through the water will be reduced to the distance between the conductor 75

82 and the metallic covering 90 at the point of break.

In Fig. 6 is shown another modified form of tail which consists of two conductors 82 and 91 embedded in the insulating material 83. In this case the conductor 83 is connected to one side of the battery 81 as shown in Fig. 1 and the conductor 91 is connected to the winding of the relay 65. In this case when the enemy vessel strikes the tail, the insulation 83 will be disrupted thus allowing the water to close the circuit between the conductors 82 and 91 which will energize the relay 65 in a manner similar to that already described.

Obviously the radius of the circular path may be chosen with regard to the speed of the torpedo and the speed of the target ship so that a hit is most probable under average conditions. This radius may be adjusted by varying the movement of the piston 51 or by changing the leverage of the arm 55.

Although only a few of the various forms in which this invention may be embodied have been shown herein, it is to be understood that the invention is not limited to any specific construction but may be embodied in various forms without departing from the spirit of the invention or the scope of the appended claims.

What is claimed is:

1. In combination with a torpedo, steering means for controlling the course thereof, a trailing wire insulated from the surrounding water, redirecting mechanism for altering the course of said torpedo, means to render said steering means ineffective and to render said redirecting mechanism effective and means actuating said last means in response to completion of the circuit to said trailing wire through the surrounding water when the insulation is disrupted by contact with the hull of a target ship.

2. In combination with a torpedo, steering means, redirecting mechanism for altering the course of said torpedo, a pair of trailing conductors normally insulated from each other, and means actuating said redirecting mechanism in response to completion of a circuit between said conductors through the surrounding water when the insulation is disrupted by contact with the hull of a target ship.

3. In combination with a torpedo, steering means therefor, redirecting mechanism for altering the course of said torpedo, a trailing antenna comprising a central conductor having a coating of insulation and a covering of relatively fragile conducting material surrounding said coating, and means actuating said redirecting mechanism in response to completion of a circuit between said central conductor and said covering through the surrounding water caused by disruption of the covering and insulation caused by contact with the hull of a target ship.

4. In combination with a torpedo two trailing conductors normally insulated from each other and from the surrounding water and means responsive to completion of a circuit between said conductors for causing said moving body to change its course.

5. In combination with a torpedo, a trailing

wire insulated from the surrounding water and adapted to contact with the hull of a target ship when the torpedo passes in front thereof, means for initially directing said torpedo toward the target ship, means to change the course of said torpedo and means actuating said last means in response to completion of the circuit to said trailing wire through the surrounding water when said insulation is disrupted by contact with said hull.

6. In combination with a torpedo, a trailing wire insulated from the surrounding water and adapted to contact with the hull of a target ship when the torpedo passes in front thereof, means for initially directing said torpedo toward the target ship, means to re-direct said torpedo toward said ship, and means actuating said last means in response to completion of the circuit to said trailing wire through the surrounding water when said insulation is disrupted by contact with said hull.

7. In combination with a torpedo, a trailing wire insulated from the surrounding water and adapted to contact with the hull of a target ship when the torpedo passes in front thereof, means for initially directing said torpedo toward the target ship, means to change the course of said torpedo, a relay adapted to actuate said last means and means actuating said relay in response to completion of the circuit to said trailing wire through the surrounding water when said insulation is disrupted by contact with said hull.

8. In combination with a torpedo, a trailing wire insulated from the surrounding water and adapted to contact with the hull of a target ship when the torpedo passes in front thereof, means for initially directing said torpedo toward the target ship, means to re-direct said torpedo toward said ship, means actuating said last means in response to completion of the circuit to said trailing wire through the surrounding water when said insulation is disrupted by contact with said hull and means for setting said re-directing mechanism for altering the course of the torpedo to either port or starboard.

9. In combination with a torpedo, a trailing wire insulated from the surrounding water and adapted to contact with the hull of a target ship when the torpedo passes in front thereof, means for initially directing said torpedo toward the target ship, means to change the course of said torpedo, a relay adapted to actuate said last means, means actuating said relay in response to completion of the circuit to said trailing wire through the surrounding water when said insulation is disrupted by contact with said hull, and means rendering said relay inoperative until said torpedo has travelled a predetermined distance.

10. In a torpedo, an insulating trailing conductor, means responsive to completion of the circuit to said conductor through the surrounding water when the insulation is disrupted by contact with the hull of a target ship to set up an electric impulse and means responsive to said impulse to re-direct the torpedo on a course designed to increase the possibility of a hit.

ELLISON S. PURINGTON.
